UNITED STATES PATENT OFFICE

152,400

DESIGN FOR AN AUTOMOBILE

Virgil M. Exner, South Bend, Ind., assignor to
The Studebaker Corporation, South Bend, Ind.,
a corporation of Delaware

Application October 10, 1946, Serial No. 133,869

Term of patent 7 years

(Cl. D14—3)

To all whom it may concern:

Be it known that I, Virgil M. Exner, a citizen of the United States, residing at South Bend, in the county of Saint Joseph and State of Indiana, have invented a new, original, and ornamental Design for an Automobile, of which the following is a specification, reference being had to the accompanying drawings, forming a part thereof.

In the drawing:

Figure 1 is a perspective view of an automobile showing my new design, looking generally to the rear and side thereof;

Figure 2 is a side elevation of the automobile of Figure 1;

Figure 3 is a front elevational view of the automobile of Figures 1 and 2; and

Figure 4 is a rear elevational view of the automobile of Figures 1 and 2.

The characteristic features of my design reside in the portions shown by means of full lines.

I claim:

The ornamental design for an automobile, as shown and described.

VIRGIL M. EXNER.
